UNITED STATES PATENT OFFICE.

GEORGE LEWIS, OF SOUTH BOSTON, MASSACHUSETTS.

TOOL HANDLE.

Application filed June 6, 1921. Serial No. 475,196.

To all whom it may concern:

Be it known that I, GEORGE LEWIS, a citizen of the United States, residing at South Boston, in the county of Suffolk and State of Massachusetts, have invented certain new and useful Improvements in Tool Handles, of which the following is a specification.

This invention relates to improvements in tool handles. It relates more particularly to that type of tool handle in which the same handle is adapted to serve for various tools each of which is insertible separately therein for use. Handles of this sort have long been known, but in all such handles, so far as I am aware, the tool after insertion must be secured to the handle; and thereafter, it must be unfastened before it can be withdrawn.

It is among the objects of the present invention to provide a handle into which the shank of a tool may be slipped easily, and from which it may be removed as easily, and yet which holds the tool so as to enable the user to perform all the ordinary operations for which the tool is adapted. It is a further object to thus hold the tool without the tightening of screw threaded clamping members being required, nor the driving in of wedge members to make a binding fit. It is a still further object to provide for protecting the handle from the blow of an auxiliary tool, as a hammer, by providing for the direct transmission of the force of the blow through the handle, without affecting the grip portion thereof. Although the type in which single ended bits are slipped into a neck provided for them is the form herein shown as especially preferred, certain parts of the invention are applicable to handles in which double bits with a blade at each end, are received with the handle encasing one of the blades and with said blade co-operating in the positioning of the blade which is set for use. The first mentioned objects are accomplished by providing a handle comprising a bar of channel iron, looped so as to form a hand-grip portion and a socket or neck portion, the latter being below or forward of the former; the ends of the looped iron being brought together in approximate parallelism. The socket-forming ends of the iron are held together by ferrules, carrying spring strips or leaves which so regulate the clamping effect of the ferrules that the frictional grip on the shank of the tool

is sufficiently great to retain it in the socket during ordinary use of the tool, yet not so great as to prevent the instant and easy withdrawal or insertion of the tools by hand. Within the hand-grip portion of the iron, and extending part way within the socket portion is a member constituting a bumper for the end of the tool which enters the socket. This bumper is so retained in the handle as to transmit directly to the shank end of the tool any blow delivered on the butt end of the looped iron, thus protecting the handle itself from the danger of injury usually resulting from such blows, and preventing absorption of the blow by the body of the handle. This in turn permits the body of the handle to be made of molded rubber which is both economical for manufacture of desired oval or irregular shape, comfortable for resiliency and grip, and capable of being made at the same time strong and tough.

One form of handle having a square-holed socket is illustrated in the accompanying drawings but it will be manifest the handle could be made to accommodate shanks of different shapes, the drawing being merely illustrative of the principles of the invention. The patent is intended to cover, by suitable expression in the appended claims, whatever features of patentable novelty exists in the invention disclosed.

In the drawings:

Figure 1 is an axial section of a tool handle embodying the invention;

Figure 2 is a perspective of the bar alone after being formed in shape for assembling in the handle;

Figure 3 is a section on line 2-2 of Figure 1;

Figure 4 is a section on line 4-4 of Figure 1 looking from the tool end;

Figure 5 is an end view of the handle looking toward the butt end;

Figure 6 is a view of the handle assembled, with part of the neck portion cut away;

Figure 7 is a view showing a modification of the bar loop;

Figure 8 is a perspective of the butt end of the bar loop shown in Figure 8;

Figure 9 shows a modification of the fillers;

Figure 10 is a section on line 10-10 of Figure 9;

Figure 11 is a view partly in section showing modifications of the filler and bumper;

Figure 12 is a section on line 12—12 of Figure 11;

Figure 13 is a view partly in section, showing still other modifications of the filler, 5 and also of the bar loop;

Figure 14 is a section on line 14—14 of Figure 13;

Figure 15 is a view partly in section and somewhat enlarged, showing the relative 10 positions of the bar ends when the ferrules and leaf springs are removed;

Figure 16 is similar to Figure 15, but shows the positions of the parts when the leaf springs are applied; and

15 Figure 17 is a similar view showing the bar ends, leaf springs and ferrules, ready to receive the tool shank.

Referring to the drawings; a bar of channel iron 10 is bent at its middle portion 20 12 and looped back on itself until its ends 14 and 16 are brought together in approximate parallelism to enable their channels to coact to form a socket portion 18, of appreciable length, in which the shank end or tang 25 20 of the tool (not shown,) may be inserted a limited distance. This limit is determined by a bumper 22, which extends from the socket portion rearward through the center of the handle between the looped or curved 30 section 10' of the channel iron, into contact with the middle portion 12 of the latter. Although illustrated as completely filling the space surrounded by the channel iron, this bumper might be a piece of straight rectangular or cylindrical stock lying within 35 this space and reaching from the looped end of the handle into the socket portion. The section of the bumper within the socket holds the bumper in axial alignment within 40 the tool handle, which alignment may be further assured by a pair of blocks 24 and 26 constituting fillers to the handle, for filling out or finishing the hand-gripping portion, which blocks centrally rest against the 45 bumper, or may do so, and the sides of the iron, and aid in retaining the former in proper position with respect to the latter. The pressure of these blocks on the loop 10', however, must be sufficiently small to permit 50 movement of the ends 14 and 16 toward and away from the axis of the handle. These blocks may be held in place by any suitable means, such as the rivets 28, there being a plate 30 under the rivet heads to 55 protect the blocks and distribute the clamping effect of the rivets. One benefit resulting from the use of the bumper for transmitting the force of a blow directly to the tool, is that the channel iron may be 60 greatly narrowed where it curves about the handle portion. For example, the channel sides and part of the bottom may be entirely removed leaving but a narrow strip of iron extending around the handle from 65 one side of the socket back to its other side.

If $\frac{5}{8}$ " channel iron is used, the strip 10' around the hand-gripping portion may be only $\frac{1}{8}$ " wide, thus making a relatively light though very strong handle. This reduction of metal in the handle enables a larger part 70 of the handle to be constituted by the fillers making a lighter tool that "handles" better and is better finished. These fillers may be made flush with the iron strips as shown in Figure 4 at 31, or may be made with 75 lips adapted to overly the iron strip 10' covering the iron completely from view except, of course, at the very butt of the handle where it is desirable to leave the metal exposed to receive a blow 80 as hereinbefore mentioned. This thinning down of the metallic rim and the removal of the sides of the channel does away with the ordinary stiffness of the channel iron, and makes the looped portion more or less resilient, depending upon the amount the stock is reduced, so that when bent into shape the ends of the iron may be set so as to have a tendency to remain spread a short 85 distance, thus constituting a split of the 90 neck where the shank of the tool is to be gripped between the two ends of the loop.

This spreading tendency of the socket forming ends of the channel iron is overcome and the end held together by two 95 ferrules 32 and 34, one of which 32 lies around that portion of the socket filled by the end of the bumper, and the other of which 34 surrounds the portion occupied by the shank of the tool. On each outer 100 face of the channel iron, which tends to spring outward, there lies a flat leaf spring 105 36 between it and the inside of the two ferrules. These springs provide the desired delicacy of friction for permitting the shank of a tool to be pushed in or pulled out by hand, and yet to be held therein while the tool is in use. They overcome to a degree the normal tendency of the handle 110 ends to spring apart, so that when there is no tool in the handle the socket walls are pressed in and the socket made smaller in one of its dimensions. The function of the springs and ferrules is illustrated in 115 Figures 15, 16 and 17. In Figure 15 the jaws 14 and 16 of the socket 18 are shown spread to the limit of movement due to 120 their own resiliency, and it is seen that when so spread they diverge slightly toward the tool end. When the springs 36 and the ferrule 32 are slipped on, the force of the 125 springs 36 is sufficient to overcome the spreading tendency of the jaws themselves, and cause them to move closer together as shown in Figure 16. Upon the ferrule 34 being applied around the ends of the springs 36 the latter exert still greater pressure on the 130 jaws 14 and 16, forcing them nearer together until they converge slightly toward the tool end. This result is illustrated in Figure 17.

Upon the tool shank being pushed in, the handle irons are spread against the force of the flat leaf springs until the limit of spread, as determined by the ferrules, is reached, at which time the frictional grip on the shank is sufficient to hold it with sufficient firmness for all ordinary uses which include pushing, prying, scraping, twisting and in fact everything except pulling. This frictional grip, however, due to the resiliency of the flat springs as well as to the elasticity of the jaws themselves, is easily overcome by a direct pull or push on the tool to extract it from or to insert it in the handle.

The upper ferrule 32 surrounding that portion of the socket housing the bumper, is penetrated by a pin 38 which passes loosely through the ferrule 32, the handle irons 14 and 16, and the flat leaf springs 36, thereby allowing the handle and springs to contact or expand freely. The pin is tight only with the bumper 32, whereby the transmission of a blow delivered on the end of the handle is through the bumper to the tool, and no part of this blow is transmitted by the pin to the handle or ferrule. Although the leaf springs are retained from undue displacement by the pin 38, further provision in this respect may be made by bending the springs outward and around the ferrule through which the pin passes, as shown at 36' in Figure 1. And, if desired, the other ends of the springs may be bent outward, as shown dotted at 36'', from the handle to prevent the other or free ferrule 34 from sliding off, while permitting it to be driven further along the handle in one direction, in any case when it is desired to tighten the grip on the tool, to make it more secure than the gentle friction hold construction above described, or to drive it in the other direction to loosen this grip.

Although two ferrules are shown in the drawings, one might serve, except that a finer adjustment of the frictional engagement is possible with the two ferrules as shown, than is ordinarily possible with one. These ferrules may be split on one side, as illustrated, with particular advantage if the shank grips converge slightly, as may sometimes happen, the spreading of the ferrule at the split giving a high degree of additional elastic constriction; but if this is not needed the split may be omitted.

The socket-forming ends of the channel iron may also be split lengthwise of their channels as shown at 40, to permit a slight approach of the quarters thus formed toward each other in a direction at right angles to the direction of movement of the separate ends toward each other.

Modifications of the handle of the invention are shown in Figures 7 to 14. In Figure 7, a handle is illustrated which is

adapted particularly for holding tools which are to be driven, such as chisels. A portion 12' of the channel iron at the butt of the handle is retained in its original size, shown clearly in Figure 8, with its outer 70 surface flat to constitute a driving head to receive the blow of a hammer or mallet. The sides 10'' of the channel, which are not cut away, provide suitable holding means for the end of the bumper, which may be large 75 enough to fill the channel so as to be retained therein in axial alignment with the tool.

An insulated handle for holding tools used on electrical apparatus is shown in Figures 9 and 10, in which the blocks or 80 fillers 24' 26', made of rubber or other non-conducting material, completely surround the metal, the fillers being shaped to allow the metallic loop and bumper 22' to fit within them. Large holes in the bumper, 85 through which the rivets extend, permit the passage of projecting sleeves 26'' from the filler, around the rivets, thus completely insulating the rivets from the bumper.

In Figures 11 to 14 inclusive, other forms 90 of filler and bumper are shown. In Figures 11 and 12 the filler 24'' is illustrated as made in one piece, having a groove 25 along each edge into which the strip 10' of the metallic loop may fit. In Figures 13 and 14 the iron 95 rim of the handle is not cut away, but is bent in its channel shape to form the loop. Its one piece filler 24''' has a tongue 27 along its edge which fits within the groove of the channel iron. A hole 29 extends through 100 these one-piece fillers, and into this hole the stem 31 of a bumper 22'' is inserted. This bumper is provided with a T-head portion 105 33 which intervenes between the butt end of the filler and the inside surface of the bend 12 of the bar 10, as shown in Figure 11. When thus positioned, the shank of a tool 110 may pass through the socket end 18 of the handle, and through the hole 29 in the filler until it encounters the end of the stem 31. The bumper may be reversed in position and 115 put at the other end of the loop; as pictured in Figure 13. In this case the tool shank encounters the bumper before entering the filler, being bottomed on the head 33 of the 120 bumper. If the bumper is removed from the filler, the tool may be pushed entirely through the filler until it rests on the inside surface of the bar at the butt end of the handle. It is thus possible with the single 125 handle, with the reversible bumper, and a single bit, to obtain three different lengths of tool measuring from the butt end of the handle to the operating end of the tool; or to use the same handle with removable bits 130 of three different lengths, while making the whole tool of unchanged length.

I claim:

1. A tool holder comprising a bar in loop-handle form with its ends together in near 130

parallelism and adapted to receive and encase the shank of a tool, combined with a ferrule embracing said ends; there being resilient means between the ferrule and one of said ends, whereby the latter is yieldingly pressed against the said shank.

2. A tool holder comprising a bar in loop-handle form with its ends together in near parallelism and adapted to receive and encase the shank of a tool, combined with a ferrule split longitudinally and adapted to be non-rotatably loose and tight while embracing said ends; there being resilient means between the ferrule and one of said ends, whereby the latter is yieldingly pressed against the said shank.

3. A tool holder comprising a bar in loop-handle form with its ends together in near parallelism and adapted to receive and encase the shank of a tool, combined with a ferrule embracing said ends; there being a strip of resilient material between the ferrule and outer surface of one of said ends, normally holding the said end away from the ferrule but being adapted to permit yielding of the end toward the ferrule upon the insertion of the tool shank.

4. A tool holder comprising a bar in loop-handle form with its ends together in near parallelism and adapted to receive and encase the shank of a tool, combined with a plurality of ferrules distributed along and embracing the ends; there being resilient means between each of said ferrules and the outer surface of one of said ends, whereby the end may be yieldingly pressed toward each ferrule upon insertion of the shank of a tool.

5. A tool holder comprising a bar in loop-handle form with its ends together in parallelism and constituting between them a smooth channel of uniform cross section adapted for receiving and gripping the shank of a tool, combined with means adapted to hold the said ends together with possibility of slight movement from said position; and resilient means interposed between the last said means and the said ends.

6. A tool holder comprising a bar curved into form of a handle, having a split neck portion constituting a socket for, and shank grip of, a tool, and having a looped portion; two blocks, one at each side clamped together about said loop portion, constituting fillers for the handle; and means around said neck portion for clamping said tool.

7. A tool holder comprising a bar curved into form of a handle, having a split neck portion constituting a socket for, and shank grip of, a tool, and having a looped portion; adapted for primary gripping by the hand; a filler held within the looped portion for filling the hollow of the hand and adapted for subsidiary gripping; and means coact-

ing with said neck portion for clamping 65 said tool.

8. A tool holder comprising a channel bar curved into loop form, the neck of the loop constituting a socket for, and shank grip of, a tool, and the body of the loop constituting a handle for manual gripping; combined with a filler whose edge portion fits within the channel of the bar, and whose body portion fits within the hollow of the hand; and there being means around said 75 neck portion for clamping said tool.

9. A tool holder comprising a bar curved into loop form adapted to clamp a tool shank within its neck portion, and having 80 a loop portion; two blocks of insulating material adapted to be clamped together about said loop portion to encase it, and means around the neck portion for clamping said tool shank; the said blocks providing an insulated surface for manual gripping 85 while the tool is in electrical contact with the thing on which it operates.

10. A tool holder comprising a bar whose ends together make a neck portion constituting a socket for, and shank grip of, a 90 tool, and whose middle constitutes a loop; combined with a removable filler held within the loop, providing suitable surface for manual gripping, and having an axial hole in continuation of said socket; and a T-shaped tool bumper, whose leg is adapted to stand in said hole with its head at either end of the filler.

11. A tool holder comprising a bar whose ends together make a neck portion constituting a socket for, and shank grip of, a tool, and whose middle constitutes a loop; combined with a removable filler held within the loop, providing suitable surface for manual gripping, and having an axial hole 100 in continuation of said socket; and a T-shaped tool bumper, whose leg is adapted to stand in said hole with its head interposed between the butt of said filler and the butt end of the loop.

12. A tool holder comprising a bar whose ends together make a neck portion constituting a socket for, and shank grip of, a tool, and whose middle constitutes a loop; and a filler held within the loop, providing 110 suitable surface for manual gripping, and having an axial hole; in continuation of said socket through which the tool may extend to butt against the bar at the end of the loop more remote from the neck portion.

13. A tool holder comprising a bar whose ends together make a neck portion constituting a socket for, and shank grip of, a tool, and whose middle is a thin looped portion; combined with blocks clamped together on the sides of said looped portion and providing surface for manual gripping; and a bumper between said blocks, extend-

ing in the medial plane of the handle from the inside of the butt end of said looped portion toward said neck portion for limiting the insertion of said tool shank.

- 5 14. A tool handle comprising a bar in loop-handle form having a split neck portion adapted to receive and grip the shank of a tool, and having a looped portion with filling means adapted for manual gripping; 10 a pair of ferrules about said neck portion holding it together; spring strips between said ferrules and the outside surface of said neck portion; a bumper extending from the butt end of the loop portion between said 15 fillers toward and into the neck portion, against which the end of the tool shank may rest; and a pin secured to the part of the bumper within the neck portion but passing loosely through the neck portion, the 20 spring strips and one of said ferrules, transverse to their direction of slippage, whereby blows on the butt are transmitted through the bumper to the tool shank.

15. A tool holder comprising a bar in

loop-handle form having a neck portion 25 constituting a socket for, and shank grip of, a tool, and having a looped portion with a channel-butt adapted to receive the blow of another tool; combined with a bumper extending through said looped portion into 30 said neck portion, having one end in said channel-butt and the other end in said socket, whereby the blow of the other tool may be transmitted direct through said channel-butt and the bumper to the tool 35 held in the handle.

16. A tool holder comprising a neck portion constituting a socket for, and shank grip of, a tool, and having a looped portion; combined with enveloping fillers of insulat- 40 ing material, adapted to house the said loop and provide suitable surface for manual gripping; there being insulated clamps holding said fillers together.

Signed at Boston, Massachusetts, this 31st 45 day of May, 1921.

GEORGE LEWIS.
